United States Patent

Des. 239,170

Patented Mar. 16, 1976

239,170

PORTABLE GREENHOUSE

Borg Hansen, 1568 Elsley Ave., and John P. Myers,
422 Lomond Ave., both of West Los Angeles, Calif.
90024

Filed Feb. 26, 1973, Ser. No. 336,091

Term of patent 14 years

Int. Cl. D25—03

U.S. Cl. D13—1 R

FIG. 1 is a left front perspective view of a portable greenhouse, showing our new design;

FIG. 2 is a right side elevational view;

FIG. 3 is a rear elevational view;

FIG. 4 is a top plan view; and

FIG. 5 is a bottom plan view.

We claim:

The ornamental design for a portable greenhouse, substantially as shown and described.
